PIN ROLL STRIPPER

Walter E. Mason, Dillard, Ga., assignor to James Lees and Sons Company, Bridgeport, Pa., a corporation of Pennsylvania

Filed Jan. 14, 1960, Ser. No. 2,366

3 Claims. (Cl. 226—53)

This invention relates to web feeding and controlling devices and more particularly to a pin roll stripper which permits temporarily removing a fabric web from a pin roll for the purpose of resetting the fabric on the pin roll and straightening the pattern or design.

In the finishing of textile pile fabrics such as tufted carpets, it is customary to run large rolls of the newly tufted material through various finishing processes. Before the application of latex or other backsizing to the fabric there is relatively less dimensional stability transversely of the fabric and in the feeding of such a roll it sometimes occurs that the pattern becomes distorted. It is therefore important that in feeding a roll of tufted fabric to the drier or backsizer that provision is made to permit realigning or lateral adjustment of the fabric to avoid distortion of the pattern which would otherwise become permanent after the backsizing is applied. The feeding of rolls of tufted fabric which may be as wide as 15 ft. is accomplished by means of a conventional spike or pin roll. Once the fabric is impaled on the pins of the roll any distortion present in the fabric cannot be corrected.

The present invention has for its primary object the provision of a framework rotatable around the center of the pin roll which framework can be turned by the operator to temporarily disengage the fabric from the pins and thereby permit correction of any misalignment or distortion of the fabric.

A further object of the invention is to provide a counterweighted framework comprising a series of bars which can be manually pivoted around the center of a pin feed roll to disengage a fabric normally impaled on the pins of the feed roll and to hold the fabric in an elevated disengaged position.

A still further object of the invention is to provide a plurality of transverse bars normally positioned around the periphery of a pin feed roll in a zone not contacted by a web of fabric running over the roll and means for turning the bars around the center of the roll to remove the fabric from contact with the surface of the roll and the pins thereon.

Further objects will be apparent from the specification and drawings in which:

FIG. 1 is a side view of a portion of the pin feed roll for a textile fabric treating machine such as an apron drier,

FIG. 2 is a diagrammatic sectional view showing the path of travel of the fabric passing over the feed roll of FIG. 1,

FIG. 3 is an enlarged sectional detail as seen at 3—3 of FIG. 1,

FIG. 4 is a view corresponding to FIG. 3 with the fabric stripper in a moved position to disengage the fabric from the periphery of the pin feed roll,

FIG. 5 is a sectional detail as seen at 5—5 of FIG. 1,

FIG. 6 is an exploded view showing the actuating mechanism for the stripper,

FIG. 7 is a perspective illustrating the construction of the stripper bars, and

FIG. 8 is a fragmentary sectional detail showing the manner in which the bars of FIG. 7 are secured to the pulley of FIG. 6.

The invention comprises essentially the provision of several, preferably three, bars positioned in close prox-

2

imity to the periphery of a pin feed roll. The bars are secured to rotatable supports journaled at each end of the shaft of the pin feed roll. A handle attached to one of the supports permits rotation of the bars around the axes of the feed roll from a position not in contact with the fabric to a second position in which the fabric is elevated or moved radially from the spikes on the feed roll and is then supported entirely on the bars. Either or both of the supports are desirably provided with a suitable counterweight which may be in the form of a cable wrapped around the periphery of the support and the handle may be latched in a retracted position so that when the handle is released the counterweights automatically rotate the bars and thereby strip the fabric from the roll.

Referring more particularly to the drawings, a conventional pin feed roll 10 is provided with a plurality of pins or spikes 11 around the entire periphery thereof. These pins engage a running web of textile fabric F which in the present case is illustrated as being a length of pile carpet. The feed roll 10 is journaled in vertical frame members 12 and 13 by means of bearings 14 and 15. The drive for the pin roll is through a sprocket 16 and the pin roll shaft 17 all of which represents conventional practice in feeding textile fabrics to a variety of operations such as the tufting machine, the drier, and the back-sizer.

In order to permit lateral alignment of the fabric to be achieved, I provide a pair of pulleys 20 and 21 which are freely journaled on shaft 17 at either end of the pin roll 10 and between bearings 14 and 15. The pulleys 20 and 21 support and are connected to each other by means of a plurality of bars 23, 24, and 25 (FIG. 7) each one of which is bolted to the periphery of each pulley 20, 21 by means of bolts 26 and nuts 27 (FIG. 8). The bars also have intermediate struts 29, 29 welded thereto in order to provide desired lateral rigidity in the area located centrally between pulleys 20 and 21. Either or both of the pulleys is provided with an operating lever 30 rigidly secured thereto and the lever is locked in a downward position as shown in FIG. 3 by means of a spring loaded latch 31 pivoted to bracket 32 at 33 and biased by means of an extension spring 34. A groove 35 in the periphery of each pulley carries a rope or cable 36 to which is attached a suitable series of counterweights 37. As shown clearly in FIGURE 3 the action of counterweights 37 tends to turn the pulleys and bars in a clockwise direction thus permitting the bars to raise the fabric F from the pins 11 as shown in FIG. 4. A suitable limit stop 40 secured to the frame member 13 controls the position of the bars so that the fabric F is completely disengaged from the pins 11 when handle 30 rests against stop 40 as seen in FIG. 4.

The fabric travel as seen in FIGS. 3 and 4 is in the direction of the arrows so that the stripping action progresses in a direction counter to the fabric travel thus preventing any tendency of the pins to snag in the fabric. When it is desired to re-engage the fabric with the pins, the operator turns handle 30 in a counterclockwise direction, as seen in FIGS. 3 and 4, until it is locked by the latch 31 and thus retained in the non-contact position. It will be noted that the fabric is therefore initially stripped from its trailing contact with the periphery of roll 10 and initially re-engaged at the leading contact with roll 10.

The present device provides a relatively simple and inexpensive means for disengaging a textile fabric from a pin roll and permits any lateral adjustment or re-alignment of the fabric to be made at any time. The action of the counterweight renders the operation of stripping instantaneous and automatic.

Having thus described my invention,
I claim:

1. In combination with a fabric pin feed roll, a plurality of sharp pins substantially covering the surface of said roll, a shaft on which said pin roll is mounted, a support journaled at each end of said shaft, a stripper element connecting said supports, means for rotating the stripper element and the supports around the shaft to disengage the fabric from the pins and the roll, said means including a counterweight urging the stripper element towards the fabric disengaging position.

2. In combination with a fabric pin feed roll, a plurality of sharp pins substantially covering the surface of said roll, a shaft on which said pin roll is mounted, a support journaled at each end of said shaft, a stripper element connecting said supports, means for rotating the stripper element and the supports around the shaft to disengage the fabric from the pins and the roll, said means including a counterweight urging the stripper element towards the fabric disengaging position, and a latch means for retaining the counterweight in an elevated position.

3. A fabric feeding assembly comprising a pin roll over which a textile fabric normally travels, a shaft for said pin roll, a plurality of pins around the periphery of said pin roll for impaling the fabric around a portion of the periphery thereof, a stripper element journaled on the pin roll shaft and normally positioned adjacent a peripheral point of the pin roll not engaged by the fabric, means for moving said stripper element from said normal position against the travel of the fabric to a stripping position in which the fabric is carried entirely by the stripping element, said means including a counterweight connected to the stripper element and a handle connected to the stripper element for moving said stripper element to a retracted position, and means for locking said handle in said retracted position.
